R. SUCZEK

CONDENSER

Filed July 16, 1921

UNITED STATES PATENT OFFICE.

ROBERT SUCZEK, OF PHILADELPHIA, PENNSYLVANIA, ASSIGNOR TO C. H. WHEELER MANUFACTURING COMPANY, OF PHILADELPHIA, PENNSYLVANIA, A CORPORATION OF PENNSYLVANIA.

CONDENSER.

Application filed July 16, 1921. Serial No. 485,203.

My invention relates to condensers such as employed for condensing the exhaust steam from steam engines or turbines, or for similar purposes.

5 In accordance with my invention, within a single condenser unit the condensable fluid, as steam, passes around tubes through which cooling medium passes, and passes through tubes around which the cooling medium passes, the condensable fluid preferably taking the paths described in the order named.

10 My invention resides in condenser structure of the character hereinafter described and claimed.

15 For an example of one of the various forms my invention may take, reference is to be had to the accompanying drawing, in which:

20 Fig. 1 is a longitudinal sectional view through structure embodying my invention.

Fig. 2 is a cross sectional view on the line 2—2 of Fig. 1.

25 Fig. 3 is a cross sectional view taken on the line 3—3 of Fig. 1.

Fig. 4 is a cross sectional view taken on the line 4—4 of Fig. 1.

30 Referring to the drawing, C is the condenser shell or body having on its ends the tube sheets S and S¹ held between flanges on the shell C and the end boxes A and B.

35 Extending through the tube sheets is a group D of condenser tubes of brass or other suitable material, around and between which

flows the fluid to be condensed, as steam, entering the shell C at E, the condensate collecting in the bottom of the shell C and passing out through the outlet F to the hot

40 well or any other suitable destination, the lower side of the group D being suitably spaced above the bottom of the shell C. Through this space between the lower side of the group D and the bottom of the shell C, when the structure is positioned as in-

45 dicated in Fig. 1, and thence through the passage G at the bottom of the tube sheet S flows the uncondensed steam and any uncondensable fluid in mixture therewith, as air, into the chamber H beneath the parti-

50 tion I in the end box A. The chamber H, as indicated in Fig. 3, extends to one side and upwardly in the box A between the outer wall of the box A and the extensions J¹ and J² of the aforesaid partition I. Com-

municating with this lateral portion of the 55 chamber H are the condenser tubes of a group J extending through the tube sheets S and S¹ within the shell C, and between it and the partition plate or wall J¹ extending longitudinally of the shell C between 60 the same and between the tube sheets S and S¹ the tubes of the group J discharging into the chamber K in the end box B, Figs. 1 and 4, such chamber being formed between the shell C and the partition having 65 the section or portion L, corresponding with partition I in box A, the section L¹ corresponding with the partition I¹ in the box A, the section L² corresponding with the section I² in the box A, and the sections L³ and 70 L⁴. The mixture of steam and air discharged from the tubes J into the chamber K passes through said chamber from left toward the right, Fig. 4, and enters the condenser tubes of the group M extending between the tube sheets S and S¹ and disposed within the shell C between the shell and the inclined wall or partition N substantially in register with the section L³ of the partition in the box B. The tubes of the group 75 M deliver into the chamber O, Fig. 3, disposed between the outer wall of the chamber A and a partition P, coinciding with partition N. Substantially nothing but air reaches the chamber O, and this is dis- 80 charged or drawn off by suitable pump, 85 ejector or the like through the air outlet Q.

The cooling water enters at R, and is delivered in divided streams through the passages R¹ and R² into the chambers within 90 the shell C containing, respectively, the tube groups M and J. The cooling water accordingly flows around the tubes of the groups J and M, preferably in a circuitous path as enforced by the baffles T, T¹, and 95 thereafter flows through the openings U and V in the tube sheet S¹ into the chamber W in the box B above the partition L²—L—L⁴, with which chamber communicate all the tubes of the group D, the cooling water then 100 flowing through the tubes D into the chamber in the box A above the partitions I², I¹, I and P, the water then passing off through the water outlet X.

The incoming steam therefore first comes 105 into contact with tubes of the group D, through which cooling water is flowing, such condensate as has been formed passing

through the condensate outlet F; the uncondensed remainder then passes into the chamber H of the box A and thence through the tubes of the group J to the chamber K in the box B, and thence through the tubes of the group M into the chamber O in box A, and the air passes off through the outlet Q.

The cooling water passes in divided 10 streams first around the tubes of the groups J and M, and thence through the tubes of the group D.

The water resulting from condensation of the steam passing through the tubes of 15 groups J and M is drawn off in any suitable manner, as from chambers K and O, respectively, as through the draw-off connections Y and Z, respectively.

By an arrangement of the character above 20 described, a greater amount of steam, other things being substantially the same, may be effectually condensed with a given amount of cooling water with a smaller amount of heat transfer surface, that is, with fewer 25 condenser tubes or shorter condenser tubes, or in general, with less tube surface. Or with a given tube surface and given cooling water conditions, greater amounts of steam may be condensed.

30 While I have described a form of my apparatus wherein the steam first flows around tubes through which cooling water is passed, and then through tubes around which cooling water passes, it will be understood that 35 the reverse arrangement may be employed.

As shown by Fig. 2, the group of tubes D is disposed between the shell C and the 40 downwardly inclined and convergent partitions J¹ and N, between which latter and the shell are disposed the other tube groups. By this arrangement, the steam passing 45 around the tubes of the group D is progressively condensed and thereby diminished in amount, and with the path diminishing in cross section as enforced by the converging partitions J¹ and N, the velocity of the steam remains substantially constant. In addition, the condensate produced around those tubes vertically above the partitions J¹ and 50 N collects upon those partitions and descends along them to the bottom of the shell. By this arrangement, there are procured the 55 advantages of the so-called V-shaped surface condenser, and the space between the partitions and the shell is usefully employed for the tubes of final condensers or coolers.

What I claim is:

1. A condenser unit comprising at least 60 three groups of tubes, the first group comprising the greatest number of tubes, and the other groups comprising lesser numbers of tubes, means for passing the fluid to be condensed first around the tubes of said first group and thence through the tubes

of said other groups in succession, and for passing cooling water first around the tubes of said other groups simultaneously and then through the tubes of said first group.

2. A condenser comprising a shell, end boxes thereon, a plurality of groups of tubes in said shell communicating with said end boxes, means for delivering cooling water around the tubes of one of said groups into 75 one of said end boxes and thence through the tubes of another of said groups to the other end box, and for directing the fluid to be condensed around the tubes of one of said groups into one of said end boxes and thence through the tubes of another of said groups into the other end box.

3. A condenser comprising a shell, end boxes thereon, three groups of tubes in said shell communicating with chambers in said boxes, structure for passing the fluid to be condensed around the tubes of the first of said groups into a chamber in one of said end boxes, thence through the tubes of the second group to a chamber in the other end box, and thence from said chamber through the third group of tubes to another chamber in said one of said end boxes, and for delivering cooling water in divided streams around said second and third groups of tubes into said other end box and thence through the tubes of said first group into a chamber in said one of said end boxes.

4. A condenser comprising a shell, end boxes thereon, tube sheets between said shell and boxes, a plurality of groups of tubes in said shell communicating through said tube sheets with said boxes, structure for passing cooling water around the tubes of one of said groups through said shell and a passage 105 in one of said tube sheets into one of said boxes, the tubes of another of said groups conducting the water from said one of said boxes to the other of said boxes, and for directing the fluid to be condensed around the tubes through which said water passes and through the tubes around which said water passes.

5. A condenser comprising a shell, end boxes thereon, tube sheets between said shell and said boxes, three groups of tubes in said shell communicating through said tube sheets with said boxes, partitions in said shell between said groups, means for passing streams of cooling water around the tubes of two of said groups between said partitions and said shell, one of said tube sheets having openings through which said streams pass into one of said boxes and thence through the tubes of the third group into the other of said boxes, said other of said boxes having a chamber communicating with the interior of said shell between said partitions and receiving fluid to be condensed from said shell, said chamber in said other

of said boxes delivering into the tubes of one of said groups around which the cooling water passes into a chamber in said one of said boxes, the other of said groups of tubes 5 around which the cooling water passes connecting with said chamber in said one of said boxes and with a second chamber in said other of said boxes, the fluid to be condensed first passing around the tubes of said 10 third group.

6. A condenser comprising a shell, a downwardly inclined partition dividing said shell into chambers, a group of tubes in one of said chambers, a smaller group of tubes 15 in the other of said chambers, and means for passing cooling water around said tubes of the small group and thence through all of the tubes of said first mentioned group in a single direction.

20 7. A condenser comprising a shell, downwardly extending converging partitions therein dividing said shell into three chambers, a group of tubes in the chamber between said partitions, and a group of tubes 25 in each of the chambers between each of said partitions and said shell, means for passing the fluid to be condensed around the tubes of said first group and through the tubes of said other groups, and means for 30 passing cooling water around the tubes of said other groups and through the tubes of said first group.

8. A condenser comprising a shell, two groups of relatively spaced tubes in said

shell, means forming a separate space around each group of tubes, an end box on said shell affording communication between the tubes of one group and the spaces between the tubes of the other group, and an end box 40 affording communication between the tubes of said other group and the spaces between the tubes of the first named group.

9. A condenser comprising a shell divided into chambers, two headers, a group of relatively spaced tubes in one chamber and each 45 communicating with one of said headers, a second group of relatively spaced tubes in another chamber and each communicating with the other of said headers, means providing communication between said one 50 header and the spaces between said second group of tubes, and means providing communication between said other header and the spaces between the first mentioned group 55 of tubes.

10. A condenser unit comprising a shell, two groups of tubes in said shell, means in said unit for directing a cooling medium around the tubes of one group and through the tubes of the other group in parallel 60 streams, and for directing the fluid to be condensed around the tubes of said other group and through the tubes of said one group.

In testimony whereof I have hereunto affixed my signature this 15th day of July, 1921.

ROBERT SUCZEK.
